US00D411553S

United States Patent [19]

Scholl

[11] Patent Number: Des. 411,553

[45] Date of Patent: ** Jun. 29, 1999

[54] **APPARATUS FOR MELTING AND DISPENSING THERMOPLASTIC MATERIAL**

[75] Inventor: **Charles H. Scholl**, Marina, Calif.

[73] Assignee: **Nordson Corporation**, Westlake, Ohio

[**] Term: **14 Years**

[21] Appl. No.: **29/088,651**

[22] Filed: **May 29, 1998**

[51] LOC (6) Cl. **15-09**

[52] U.S. Cl. **D15/144**

[58] Field of Search .... D15/144; 222/149, 222/146 HE, 146.5, 190, 49

[57] **CLAIM**

The ornamental design for an apparatus for melting and dispensing thermoplastic material, as shown and described.

DESCRIPTION

FIG. 1 is a top plan view of the apparatus for melting and dispensing thermoplastic material showing my new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a left side elevational view with the lid of the apparatus in the open position.

The broken line showing is for illustrative purposes only and forms no part of the claimed design.
